FINGER RING

James Raymond Powers, Livonia, Mich., assignor to
Traub Manufacturing Company, Detroit, Mich., a corporation of Michigan

Filed Jan. 22, 1962, Ser. No. 68,398

Term of patent 14 years

(Cl. D45—10)

FIGURE 1 is a perspective view of a finger ring showing my new design;

FIGURE 2 is a top plan view thereof;

FIGURE 3 is a front elevational view;

FIGURE 4 is a side elevational view as seen from the right in FIGURE 3; and

FIGURE 5 is a side elevational view as seen from the left in FIGURE 3.

The essential features of the design reside in the portions shown in full lines.

The characteristic feature of the design resides in the reflective cup for the stone formed by the swirls con-

figuration of the metal around the area where the stone is to be mounted.

I claim:

The ornamental design for a finger ring, as shown and described.
